END POST CONSTRUCTION FOR HIGHWAY GUARDRAILS AND THE LIKE

Edward J. Russert, Youngstown, and Clare L. Hinsdale, Warren, Ohio, assignors, by mesne assignments, to Mullins Manufacturing Corporation, Salem, Ohio, a corporation of New York

Application April 16, 1937, Serial No. 137,250

4 Claims. (Cl. 189—29)

The invention relates to end post construction particularly adapted for use in connection with highway guard construction, and more particularly to that form of construction in which a metal guard rail is supported in tension between opposite end post constructions and upon a plurality of intermediate posts.

Prior to the present improvements, it has been usual to provide wooden or metal posts, both for the intermediate posts and the end post constructions, and which are not adapted for being driven into position, but which require the digging of holes for the proper positioning thereof at the side of the highway, and in the case of the end post construction require the digging of enlarged holes for applying the necessary baffle means, and frequently the provision of concrete footers for each post.

In our copending application, Serial No. 137,251, for United States Letters Patent for improvements in Metal post construction, we disclose a metal post construction which is more particularly adapted for use as the intermediate post in highway guard construction.

The objects of the present invention include the provision of improved end post construction particularly adapted for use in highway guard construction, and which may include as a part thereof one or more posts including the improvements of our said copending application for U. S. Letters Patent for Metal post construction.

More particularly the objects of the present invention include the provision of end post construction particularly adapted for use in highway guard construction and which may include an end post and an anchor post each adapted for being driven into the ground at the side of the highway without requiring that a hole be dug for the placement of the post, and at the same time being provided with suitable baffle means, thereby greatly reducing the total cost of the completed highway guard construction.

The nature of the improved end post construction of the present invention may be described in general terms as including an end post preferably formed of sheet or strip metal, and adapted for being directly driven into the ground, and having provided thereon baffle means preferably formed of sheet or strip metal, and the baffle means being so arranged with the end post so as to permit the direct driving of the end post with the baffle means into the ground.

An anchor post is also provided preferably formed of sheet or strip metal and having preferably metal baffle means secured thereon and ar-

ranged so that the anchor post with the baffle means may be directly driven into the ground.

Preferably a compression brace member, preferably made of metal, is connected at opposite ends with the end post and with the anchor post, the anchor post being preferably driven so that its top is elevated only a short distance above the ground level and the brace member extending therefrom at an acute angle with the ground level, and beneath the preferably metal guard rail, one end of which is secured to the end post of each improved end post construction.

By way of example, an embodiment of the preferably all metal end post construction of the present invention is illustrated in the accompanying drawings forming part hereof, in which

Figure 1 is a fragmentary perspective view of an all metal highway guard construction including an embodiment of the present improved end post construction, portions of the ground being broken away for more clearly illustrating the details of construction, arrangement, and installation, and the highway guard construction being shown looking at the end and away from the road side thereof;

Fig. 2, a fragmentary elevation view thereof looking at the road side thereof; and

Fig. 3, a fragmentary top plan view thereof.

Similar numerals refer to similar parts throughout the drawings.

The preferably all metal end post construction of the present invention is indicated generally by 10 and is included as the end post construction of an all metal highway guard construction indicated generally by 11 and including in addition to the end post construction 10 a plurality of intermediate posts one of which is illustrated and indicated generally by 12 and a usual band steel guard rail indicated generally by 13 is secured by usual means indicated generally by 14 to the intermediate post 12, and by usual resilient and bolt means indicated generally by 15 to the end post construction 10.

As shown, the intermediate post 12 is in the form of an all metal post which may be directly driven into the ground foundation 16, and is set forth in detail in our copending application for U. S. Letters Patent for Metal post construction, executed April 8, 1937.

The improved end post construction 10 of the present invention includes the foundation 16, which may be termed a ground foundation, and which is predominantly composed of the usual material of the ground or earth at the side of a highway indicated generally by 17.

The improved end post construction furthermore includes an end post indicated generally by 18 and an anchor post indicated generally by 19 laterally spaced from each other and driven into the ground foundation 16, and a preferably compression brace member indicated generally by 20 which is preferably removably secured at one end by cap screw means 21 to a transversely extending angle connector member 23 secured as by welding to the upper end of the anchor post 19 above the level 24 of the ground foundation 16.

The other end of the brace member 20 is secured as by bolt means 25 to a transversely extending angle connector member 26 secured as by welding to the end post 18 above the ground foundation level 24 and just below the resilient bolt connector means 15 for the end of the guard rail 13.

Accordingly as illustrated the brace member 20 extends at an acute angle to the ground foundation level 24 between the anchor post 19 and the end post 18.

The end post 18 and the anchor post 19 are each formed of metal having longitudinally extending walls and having a transverse cross section the thickness of which is substantially less than its over-all width, and which may be a V transverse cross section as best shown in Fig. 3, the post being preferably formed of sheet or strip steel.

As shown both the end post 18 and the anchor post 19 are provided with formed metal caps 27 which are preferably secured to the upper ends thereof as by peripheral welds, as set forth in detail in our said copending application for U. S. Letters Patent for Metal post construction.

The end post 18 as shown is also preferably provided with the longitudinal corrugations 28 extending through a portion of its length, also as set forth in detail in our said copending application for U. S. Letters Patent for Metal post construction.

Each of the posts 18 and 19 has secured thereto longitudinally extending baffle means indicated respectively by 29 and 29' which differ from each other only as shown in the length thereof.

Each baffle means 29 and 29' extends preferably across the V opening from opposite sides of the post to which it is secured and is formed of metal 50 and has a transverse cross section the thickness of which is substantially less than its over-all width so that the baffle means is adapted for being directly driven into the ground foundation 55 with the post to which it is secured.

As shown, and preferably each baffle means 29 and 29' is in the form of a baffle plate made of corrugated metal, and the ribs and the troughs of the corrugated metal preferably extend longitudinally of the post for facilitating the direct driving of the post with the baffle means into the ground.

All the parts of the end post 18 and the anchor post 19 are preferably made of metal and the brace member 20 is also preferably made of metal, as shown a channel member.

The metal end post 18 and the metal anchor post 19 each having the metal baffle means 29 or 29' secured thereto is adapted for being directly driven into the ground foundation 16, the baffle means of each post being directly driven into the ground foundation 16 with the post to which it is secured.

In order to avoid tipping of the end post 18 and the anchor post 19 in the direction of the

pull of the guard rail 13, it is necessary that some form of baffle means be provided, but prior to the present improvements, a metal post with a metal baffle means secured thereto has not been available which, with its baffle means, could be 5 directly driven into a ground foundation.

As shown in Fig. 3, in dot-dash lines, a baffle means 29 may be secured to the opposite face of end post 18 instead of at the place shown in full lines across the V opening, or if desired, in 10 addition to the baffle means shown in full lines.

Referring to Figs. 2 and 3, a bolt support 30 is provided on end post 18 for maintaining the upper bolt 15 substantially horizontal. The purpose of this is to prevent the weight of the 15 spring section of the guard rail from sagging. The upper edge of the bolt support 30 is located preferably in a plane tangential with the bottom of the corresponding bolt hole in the closed face of the post 18; and the angle 26 is located in a 20 like manner with respect to the bottom bolt so as to similarly support the bottom bolt means 15. The bolt hole for the lower bolt may be an elongated one so that railings of different styles can be fastened by bolts to the end post 12 without interference.

The adaptability of the end post and anchor post of the present improvements with their baffle means for being directly driven into the ground foundation, greatly reduces the time and 30 thus the cost of erecting a highway guard.

The embodiment of the improved end post construction illustrated and described herein is by way of example, and the scope of the present invention is not limited to the same or to the 35 particular details thereof, but is commensurate with any and all novel subject matter contained herein, and which may at any time properly under the patent laws be set forth in claims hereof or which may originate herein, the elements of any of the claims being intended to include their reasonable equivalents.

We claim:

1. A post, for end post construction for highway guards and the like, the post being formed 45 of metal having longitudinally extending walls and having a transverse V cross section the thickness of which is substantially less than its over-all width so that the post is adapted for being directly driven into a ground foundation, and 50 the post having longitudinally extending baffle means secured to the post across the V opening and extending from opposite sides thereof and being formed of metal and having a transverse cross section the thickness of which is substantially less than its over-all width so that the baffle means is adapted for being directly driven into a ground foundation with the post.

2. A post, for end post construction for highway guards and the like, the post being formed 60 of metal having longitudinally extending walls and having a transverse V cross section the thickness of which is substantially less than its over-all width so that the post is adapted for being directly driven into a ground foundation, and 65 the post having a longitudinally extending baffle plate secured to the post across the V opening and extending from opposite sides thereof and being formed of metal having a transverse cross section whose thickness is substantially less than 70 its over-all width so that the baffle plate is adapted for being directly driven into a ground foundation with the post.

3. A post, for end post construction for highway guards and the like, the post being formed 75

- 5 of metal having longitudinally extending walls and having a transverse V cross section the thickness of which is substantially less than its over-all width so that the post is adapted for being directly driven into a ground foundation, and the post having a longitudinally extending baffle plate secured to the post across the V opening and extending from opposite sides thereof and being formed of corrugated metal.
- 10 4. A post, for end post construction for highway guards and the like, the post being formed of metal having longitudinally extending walls

and having a transverse V cross section the thickness of which is substantially less than its over-all width so that the post is adapted for being directly driven into a ground foundation, and the post having a longitudinally extending baffle plate secured to the post across the V opening and extending from opposite sides thereof and being formed of corrugated metal and the ribs and troughs of the corrugated metal extending longitudinally of the post.

EDWARD J. RUSSETT.
